UNITED STATES PATENT OFFICE.

MARTIN OLSEN, OF MANCHESTER, MASSACHUSETTS.

NON-SINKABLE SHIP.

1,321,325.

Specification of Letters Patent. Patented Nov. 11, 1919.

Application filed February 13, 1918. Serial No. 216,858.

To all whom it may concern:

Be it known that I, MARTIN OLSEN, a citizen of the United States, residing at

5 Manchester, in the county of Essex and State of Massachusetts, have invented new and useful Improvements in Non-Sinkable Ships, of which the following is a specification.

The object of this invention is to provide 10 a ship which shall be substantially proof against mines and torpedoes, and capable of transporting troops and merchandise with comparative safety during time of war.

In accordance with my invention, that 15 portion of the hull which is below the water line is filled with buoyant bodies, such as metal cases, which are held in place with spaces between them, to absorb the effect of an explosion, and is provided with relatively 20 large vents or stacks leading to the exterior atmosphere. I appreciate that the utilization of the space in the hull, for receiving the pontoons, cuts down the carrying capacity of the ship, but I believe that this is 25 compensated for by decreasing the number of the ships sunk.

A ship embodying my invention has the 30 interior of the hull divided longitudinally and transversely by open-work gratings or partitions, into communicating compartments, and in each compartment are stacked the cases so as completely to fill it. Spacers are employed to separate each individual 35 case from those adjacent, and leave communicating air spaces or channels. Then from each compartment, a large vent or stack is carried through the upper decks and opens into the atmosphere, for quickly 40 carrying away the gases formed or released by the explosion.

It is preferable that the cases should in 45 the main be identical in construction or interchangeable, and that each should consist of an air-tight sheet-metal box, so that by their buoyancy, even though a large hole be formed in the hull, the vessel will be kept afloat thereby.

On the accompanying drawings,—

50 Figure 1 represents in plan view a vessel, this figure being more or less diagrammatic and not showing anything more than the hull, the vents, and in broken lines the open-work partitions.

55 Fig. 2 illustrates a longitudinal section through the ship.

Fig. 3 represents a transverse section thereof on the line 3—3 on a somewhat larger scale.

Fig. 4 represents in section one of the hollow cases or buoyant bodies.

Fig. 5 is an isometric perspective view illustrating how they are stacked in rows and piles.

Fig. 6 illustrates a spacer which is located 65 at the corners of eight pontoons.

The drawing does not illustrate any of the features of the ship or vessel except those which embody the present invention, it being 70 understood that the vessel will be equipped with suitable propellers and gas or steam engines for furnishing power thereto.

I have not attempted to illustrate the 75 various decks which are arranged above the main deck, as these form no part of the present invention. The hull of the ship is shown in outline in Figs. 1, 2 and 3, and it is provided with what may be termed a main deck *a* which is preferably a few feet 80 above the water line which is indicated in Fig. 3 at *xx*. The ship is divided longitudinally and transversely by various partitions, the longitudinal partitions being indicated at *bb* and the transverse partitions 85 at *cc*. There may be as many of these partitions as desired. Extending from the main deck and terminating above the upper deck there are a number of relatively 90 large vents or stacks *d*, each of which is shown as leading from two of the compartments. The partitions, as previously explained, are preferably open-work. They 95 may be made of metal bars, angle irons or the like, as indicated at *e* in Fig. 3, so that, while they actually divide the space below the main deck into compartments, the said compartments communicate with each other.

Within the several compartments there 100 are stacked or piled numerous hollow cases or boxes indicated at *f*. Each consists of a sheet metal shell *h* having closed ends *i* so that it is air-tight. Preferably these are oblong in shape so that they can be arranged in rows and piles as shown in Fig. 5. They 105 are separate each from the others but are stacked in such way that spaces or communicating air channels are left between them, and, to this end, I utilize spacer blocks *j*. These blocks may be secured to the cases 110 in such way that, when they are piled, the cases will be spaced or separated. Some of

the cases may be shaped so as to fit in irregular spaces caused by the curvature of the sides and bottom of the ship's hull. They should be so stacked in the various 5 compartments that they are held against movement.

In Fig. 6, the cubical spacer block *k* has at each of its eight corners a reentrant recess to receive the corner of one of the oblong 10 pontoons.

The spacers provide numerous communicating horizontal and vertical air channels between the cases or buoyant bodies through which gases resulting from an explosion 15 will travel to the vents or stacks, which are always open to the atmosphere, and be dissipated into the external air. Even though water should pass through a hole in the hull and fill the channels, the pontoons, by their 20 buoyancy, will keep the ship afloat.

In the event that a torpedo should penetrate the shell or side of the vessel, and should explode in the interior thereof, the 25 expanding gases will fill the channels or spaces between the cases and a large proportion will escape through the relatively large vents which communicate therewith. Doubtless a number of the cases will be crushed, but there will be a sufficient number uninjured 30 to keep the vessel afloat by their buoyancy. Even though the whole hull should be filled with water below the main deck *a*, the vessel will remain afloat. In all probability a vessel could be destroyed by continued shell fire, but the explosion of one or 35 even several torpedoes in the hull will not cause the sinking of the ship.

It will be noticed that, in Fig. 1, to the right of the last partition *c* at the stern,

there are no longitudinal partitions and no 40 cases. This space is left for the reception of power-transmitting mechanism, gas engines or the like.

What I claim is:—

1. A ship having the space below its main 45 deck filled with individual airtight cases, and means for spacing said cases apart vertically and horizontally to provide communicating horizontal and vertical air channels.

2. A ship comprising a hull, a main deck, 50 open partitions dividing the space below the main deck into compartments, individual buoyant bodies filling said compartments, and spacers for spacing said bodies apart both vertically and horizontally to form 55 communicating air channels.

3. A ship comprising a hull, a main deck, partitions dividing the space below the main deck into compartments, individual airtight 60 cases substantially filling said compartments and spaced apart to provide communicating horizontal and vertical air channels, and vents communicating with said air spaces leading from said compartments upwardly through said main deck.

4. A ship comprising a hull, a main deck, openwork partitions dividing the space below the main deck into communicating compartments, individual airtight cases substantially filling said compartments, spacers for 70 spacing said cases vertically and horizontally and forming air channels, and vents communicating with said channels and leading from said compartments upwardly through said main deck.

In testimony whereof I have affixed my signature.

MARTIN OLSEN.
